UNITED STATES PATENT OFFICE.

JOHN L. PARKES, OF CHICAGO, ILLINOIS, ASSIGNOR OF ONE-HALF TO ALBERT C. BROWN, OF CHICAGO, ILLINOIS.

ENGINE-PRIMING DEVICE.

1,162,803.

Specification of Letters Patent.

Patented Dec. 7, 1915.

Application filed November 4, 1912. Serial No. 729,192.

To all whom it may concern:

Be it known that I, JOHN L. PARKES, a citizen of the United States, and a resident of Chicago, Cook county, Illinois, have invented certain new and useful Improvements in Engine-Priming Devices; and I do hereby declare that the following is a full, clear, and exact description of the same, reference being had to the accompanying drawings, and to the numbers of reference marked thereon, which form a part of this specification.

This invention relates to improvements in starting or priming devices for internal combustion engines, and has particular reference to improvements in priming devices for gas or gasoline engines.

It is an object of this invention to provide an engine priming device of simple construction, consisting of but few parts, and adapted to automatically and positively close the passage connecting the supply of priming fluid with the engine, when the device is not in use, and to be arranged or mounted in a number of different relative positions.

It is a further object of this invention to provide a priming device for hydro-carbon engines, which can be easily and quickly installed, and which carries within itself the supply of priming fluid.

It is also an object of this invention to provide a manually operable pump, particularly adapted for forcing the priming fluid from the supply reservoir to the engine, which shall be of simple construction, and which shall carry within itself a positive shut off cock automatically closed when not in use, and which is so associated with a supply vessel of priming fluid removably secured thereto, that the whole presents a compact and neat appearance, which can be easily and quickly installed for use.

The invention consists in a priming device for internal combustion engines, embracing a combined pump and shut off cock associated with a supply of starting fluid and connected to deliver hydro-carbon to the engine.

The invention further consists in a pump of simple construction, having inlet and discharge passages connecting with its base, and having its plunger formed to positively close said passages when the pump is not in operation.

The invention further consists in a manually operable pump associated with a supply reservoir of hydro-carbon or other priming fluid, removably secured thereto, the plunger of the pump being adapted to close, at one limit of its movement, the inlet and outlet passages of the pump.

The invention further consists in a manually operable pump combined with a supply reservoir adapted to contain priming fluid, the pump and reservoir being adapted to be associated in different relations for the purpose of arranging the device so that it can be suitably mounted in different positions.

The invention further consists in the association of mechanisms and in the features of construction, and the arrangement of parts whereby the above and other objects are attained, as hereinafter described, and particularly pointed out in the claims.

In the drawings: Figure 1 is a side elevation of an automobile engine and associated parts, and illustrates the installation of the device embodying my invention, upon the same. Fig. 2 is an enlarged vertical central section of the pump and associated reservoir. Fig. 3 is a side elevation showing a method of supporting the reservoir in position on the pump. Fig. 4 is a side elevation of the reservoir and a portion of the pump illustrating two relative positions in which the pump and reservoir can be placed. Fig. 5 is a side elevation showing the pump arranged in horizontal instead of vertical position. Fig. 6 is a side elevation of the reservoir and a portion of the pump showing a modified form of reservoir retainer. Fig. 7 is a horizontal section on line 7-7 of Fig. 6. Fig. 8 is an enlarged horizontal section on line 8 of Fig. 1, showing a method of connecting the delivery pipe to the inlet manifold of the engine. Fig. 9 is a vertical section on line 9-9 of Fig. 8. Fig. 10 is a diagrammatic view illustrating a method of placing the pipe connection in position to secure it to the manifold of an engine. Fig. 11 illustrates a modification of my invention in which the priming fluid is pumped direct from the supply pipe.

As shown in the drawings: In starting automobile engines it is desirable to supply a sufficient quantity of gas or fluid to the cylinder without undue waste, and I therefore inject a small quantity of starting or priming fluid into the inlet manifold of the

engine at such a point that the fluid will be carried into the cylinder of the engine, whose intake valve is opened and receiving or drawing in fuel gas.

5 A priming device of the character herein described is particularly adapted to be installed upon automobiles which are not provided with suitable priming devices. It is desirable that the device be capable of being 10 installed with the least amount of labor, and furthermore, as the intake manifolds are usually made of cast metal, it is necessary to drill or make an opening therein through which to insert the supply pipe, and I have 15 devised a unique pipe connection which not only facilitates the installation of the device, but further acts to direct the starting fluid within the manifold in the direction which will materially assist in causing the 20 primary fluid to enter the cylinders.

In said drawings A represents an automobile engine installed in position and provided with an inlet manifold B.

C represents generally, the combined 25 pump and reservoir, which is connected to the manifold B by means of the pipe D.

As shown in Figs. 1 and 2, the pump 2, is arranged in vertical position and the reservoir 3, is mounted upon the lower end of the 30 pump and depends therefrom. The device itself is mounted upon the dashboard 4, of the automobile by means of a suitable clamping bracket 5. The pump 2, comprises a cylinder 2' within which is mounted a hollow 35 plunger 2'', which projects from the upper end of the cylinder 2', having upon its upper or outer end an enlarged handpiece 5, by means of which the plunger can be operated within the cylinder. The upper end of the 40 cylinder is closed by means of a suitable adjustable packing 6, which effectually prevents the escape of any fluid at this end of the pump. The cylinder of the pump is mounted at its lower end upon a base member 7, which is provided with a central conical cavity 8, adapted to receive a similarly shaped head 9, provided upon the lower or inner end of the pump plunger 2''. This 45 base 7, is provided with two substantially 50 identical nozzles 10 and 11, projecting therefrom and arranged, one in substantial axial alignment with the pump cylinder and the other arranged to project substantially at right angles thereto. The projection 10, is 55 provided with a central passage 12, which opens at its inner end into the base of the conical opening 8 and the nozzle 11, is provided with a similar central passage 13, opening through the side wall of the conical opening 8. The head 9, of the pump 60 plunger is conformed to the conical opening 8, with a valve fit so that when the pump plunger is forced to the lower limit of its movement and the head 9 is seated in the 65 conical opening 8, in the manner of a coni-

cal stop cock, it effectually prevents the flow of liquid from the inlet opening 12, to the outlet opening 13 or vice versa.

The body 3', of the reservoir 3, is made of glass or any other suitable material, and is 70 provided with a metal cover 14. The cover is secured to the pump by means of a screw plug 15, adapted to be mounted in a threaded opening 16, provided in the projecting nozzle 10, and in direct communication with 75 the inlet passage 12. As shown, the plug 15, carries a ball valve 17, and a small light compression spring 18, which serve as a check valve to prevent the return of the liquid to the reservoir after it has once been brought 80 up by the pump, and is extended to the bottom of the reservoir by means of the suction pipe 19, connected to the same by a union 20. The cap or cover 14, and the body 3', of the reservoir, are provided with engaging screw 85 threads 21, so that the glass reservoir can be readily removed from the pump for cleaning and filling.

A bail 22, is pivotally mounted on the base 7, of the pump in position to surround the reservoir and bear upon its lower end and thereby prevent the unscrewing of the reservoir 3', from the cover 14. The center of the pivotal connection of the bail with the base is arranged at the intersection of the 90 center line of the two nozzles 10 and 11, and these nozzles are equal in length from this intersection. The pump is made in this manner so that the reservoir can be interchangeably mounted upon the nozzle 10, as shown 95 in Figs. 1 and 2, or upon the nozzle 11, as shown in dotted lines in Fig. 4, and in full lines in Fig. 5, the bail 22, serving with equal efficiency to prevent the removal of the reservoir in either of its positions. The bail comprises a flat strip of spring metal bent into 100 U form and having its ends arranged for proper connection to the base 7. When in its normal position it bears upon the lower end of the glass reservoir and thus prevents 105 it from becoming loosened. The bail is of such shape that it can be readily lengthened to a sufficient extent to permit it to be rotated on its pivots to free it from the glass reservoir for the purpose of permitting the 110 removal of the reservoir, and for this purpose the sides 23, of the bail are bowed, as clearly illustrated in Fig. 3.

It is obvious from the construction described that the bail may be removed from 115 contact with the glass reservoir by pressing the side members 23, of the bail toward each other, thereby permitting the bail to be swung free of the reservoir.

The nozzle 11, as shown in Fig. 2, receives 125 a screw threaded connection 24, which carries a check valve, similar to the valve 17, mounted in the connection 15, and serves to prevent the return of the starting fluid 130 which has been forced out of the pump 130

through the outlet passage 13. As shown, said connection 24, is connected to the engine by means of the pipe D, as hereinbefore described. It is obvious that the movement 5 of the plunger within the cylinder will draw the priming fluid contained in the reservoir 3, into the pump cylinder and force it through the pipe D, to the engine, and that when the pump is not in use, if the plunger 10 is forced to the inner limit of its movement, it will effectually prevent the return of the starting fluid from the pipe D, into the pump or into the reservoir 3. To prevent the possibility of the plunger not being re- 15 turned to the inner limit of its movement, a light spiral compression spring 25, is provided, which is mounted within the cylinder 2' of the pump and is adapted to bear at its inner end upon the upper end of the head 20 9, consequently the plunger 2" will be automatically returned by the spring 25, to the inner limit of its movement regardless of the position in which the operator leaves the plunger. A small relief passage 26, is pro- 25 vided through the plunger head 9, which opens to its end through the inner end of the head 9, and at its other end opens into the pump cylinder 2'. The relief passage 26, serves two purposes, it prevents the possible 30 accumulation of fluid above the head 9, which might prevent the easy operation of the pump and it further serves to permit the outflow of liquid from beneath the plunger into the cylinder when the plunger is forced 35 to the lower limit of its movement. If the liquid was not released from beneath the head 9, it might serve to prevent the final seating of the head in the conical opening 8.

In order that the device can be easily and 40 conveniently installed in connection with automobile engines, a unique pipe connection E, is provided by means of which the pipe D, can be connected to the manifold B. As shown the connection E, comprises a 45 screw thread pipe nipple 30, adapted for convenient connection at one end with the pipe D, and which has pivotally mounted on its other end a cross bar member 31, which has a cross section of U-form and may be ar- 50 ranged within the manifold B, in longitudinal position as indicated in dotted lines in Fig. 1, and as also shown in Fig. 8. The cross bar member in such position serves to break up and direct the flow of priming 55 fluid from the nipple 30 longitudinally of the manifold B, directing it toward the cylinders of the engine. The cross bar 31, is mounted upon the inner end of the nipple by means of a pivot pin 32, arranged somewhat 60 nearer one end of the cross bar than the other. In mounting this connection E, in a manifold, a hole 33, is provided in the mani- 65 fold in proper position to receive the connection, and as clearly illustrated in Fig. 10, when the connection is entered through the

hole, the longer end of the cross bar 31, serves to rotate the cross bar to a right angle relation to the nipple so that when the nut 34, on the nipple is screwed down to tighten the nipple in the manifold, the cross bar will 70 set itself at right angles to the nipple and thus retain the nipple in position. The direction in which the priming fluid escapes from the U-shaped cross bar is further aided by closing over or capping the inner end 35, 75 of the nipple and providing a plurality of small discharge openings 36, therein, which are arranged to emit the starting fluid longitudinally of the U-shaped cross bar 31, toward both ends thereof. For the purpose 80 of making a tight joint between the connection E, and the manifold, a curved metallic washer 37, is provided, and beneath the washer is provided a soft washer 38, made of asbestos or other suitable material. As 85 shown, the metallic washer 37, is curved substantially to the curvature of the manifold so that when pressed against the soft washer 38, by the nut 34, it will serve to make a tight joint between the nipple and the outer 90 surface of the manifold.

Fig. 6 illustrates a modification of the device for holding the reservoir 3, in place. This device is similar to the bail 22, in that it is similarly pivoted to the base of the 95 pump, but instead of being carried completely around the bottom of the reservoir, it is provided with a resilient clasp member 39, which is adapted to clasp the body of the reservoir. Said clasp member 39, is se- 100 cured to the side bars 23, of the bail, which, as shown in Fig. 7, is U shaped, and is adapted to be sprung over the cylindrical body of the receptacle and clasp it with sufficient pressure to prevent it from becoming loosened from the screw cap 14.

Fig. 5 shows the device C, installed on a dash board 4, with the pump cylinder ar- 110 ranged in horizontal position instead of in vertical position, as illustrated in Figs. 1 and 2, and when arranged for such installation the reservoir 3, is changed from the lower end of the pump, as shown in Figs. 1 and 2, to the side connection 11, and obvi- 115 ously the two ball check valves which serve to prevent the return of the starting fluid from the pipe D, to the reservoir 3, are also reversed in position. The only change in the construction of the pump for the instal- 120 lation shown in Fig. 5, is that clamp 40, is of slightly different form from the holding clamp 5, shown in Figs. 1 and 2.

The operation is as follows: In using my device the reservoir 3, having been supplied with starting fluid and the device having 125 been installed in position, it is only necessary to actuate the plunger 2" outwardly and inwardly, each outward stroke drawing liquid from the reservoir and each inward stroke forcing the liquid from the pump 130

cylinder into the manifold of the engine and distributing it longitudinally therein. It is obvious that instead of providing the pump with a small individual reservoir carried thereby, the intake 19, could be extended to some other source of supply of starting fluid such as the supply pipe X. There are, however, certain advantages to be gained by the use of the individual reservoir arranged in position to be conveniently inspected. In the first place it is convenient with the use of such a reservoir to use a more volatile fluid for starting the engine than is provided for its fuel supply. This feature is convenient particularly for starting engines in cold weather, as the gasoline which is ordinarily used at the present time is not likely to be of such a quality that it can be volatilized easily enough to start the engine without delay. Another advantage is that the amount of starting fluid which the receptacle contains can be easily seen at any time. The pump having been operated to discharge the priming fluid from the reservoir into the manifold of the engine, it is not necessary to manually operate any valves for the purpose of shutting off completely the connection between the reservoir and the manifold as the spring 25 automatically forces the plunger 2" to the lower limit of its movement seating the head 9, in the conical opening 8, and completely shutting off connection as hereinbefore described. It should be understood that in the use of a device of this character, a positive shut off valve is an essential element for the reason that after the engine has been started the suction of the cylinders upon the inlet manifold of the engine will be transmitted to the auxiliary reservoir through the connecting pipes. Should this action be permitted the liquid fuel would be drawn through the pump into the manifold and would seriously disturb the action of the engine. The automatic closing of the positive shut off valve in my device relieves the operator of any necessity of manually closing the connection between the auxiliary supply and the engine, as he is assured that once he has primed the engine and released the pump plunger no further fuel can enter the inlet manifold from the auxiliary supply. While my invention is particularly adapted for use upon an automobile, it will be obvious that it is not limited to the production of a priming device for this particular use, and furthermore, while I have shown my device as being provided with a reservoir attached to the pump, it will be equally obvious that the function of the device, in so far as it relates to the forcing of a starting fluid into the manifold of an engine, can be performed with equal facility by connecting the pump directly or indirectly to a larger supply of gasoline or other starting fluid,

namely, the main supply of liquid fuel, as shown in Fig. 11, which is used in the engine itself.

As it is obvious that many modifications of my invention will readily suggest themselves to one skilled in the art, I do not purpose limiting the patent issued upon this application for patent otherwise than necessitated by the prior art.

I claim as my invention:

1. In a priming device for internal combustion engines a pump casing, a piston movable therein, a spring acting to normally return said piston to one end of said casing, passages through said piston for permitting a flow of fuel therethrough, similarly constructed inlet and outlet nozzles arranged at right angles to one another on the lower end of said pump casing, a pipe adapted to be connected to one of said nozzles and to the manifold of an engine, a reservoir for fuel adapted to be connected to the other of said nozzles, said pipe and reservoir interchangeable on said respective nozzles, and a pivoted resilient bail member attached to said pump casing and adapted to engage around said reservoir to assist in maintaining the same associated with said pump casing.

2. In a device for forcing priming fluid into an internal combustion engine, a pump, a priming-fluid-containing reservoir removably mounted on the pump, communication between the reservoir and the engine, said communication including the pump cylinder, a plunger operable in the pump cylinder to draw liquid from the reservoir and to force it into the engine, a conical head at its inner end adapted to seat at one limit of its movement in a conforming opening in the base of the pump and thereby positively to close the communication between the reservoir and the engine, and a relief passage extending through said conical head and adapted to permit the outflow of liquid from beneath the head into the cylinder when said head is forced to its lower limit of movement.

3. In a device for forcing a combustible fluid into an internal combustion engine, a manually operable pump, a pipe connecting the cylinder of the pump to a source of supply of the fluid, a second pipe connecting the cylinder of the pump with the engine, the base of the pump having a conical opening communicating with the interior of the pump and into which both of said pipes enter, a plunger operable within the pump and having a conical head at its inner end adapted to be seated in said conical opening and thereby shut off communication between the source of supply of fluid and the engine.

4. A compound pump and shut off valve comprising a pump cylinder having in its base a conical shaped opening, an inlet and

an outlet pipe entering the pump in its base, one pipe at least thereof entering through the conical wall, a plunger projecting through the upper end of the pump cylinder, and a conical head on the inner end of the plunger adapted to be seated in the conical opening to prevent the flow of fluid between the inlet and the outlet openings.

5. In a priming device of the class described the combination with a pump, a piston movable therein, a spring acting normally to return said piston to one end of said pump, a plurality of similarly constructed nozzles at one end of said pump, a 10 supply reservoir and an outlet pipe adapted to be interchangeably connected upon said nozzles, means having threaded engagement with said reservoir for supporting the same connected to said pump, and a pivoted resilient bail adapted to engage around said reservoir when connected upon either one of said nozzles to assist in maintaining the same in position.

6. A manually operable reciprocating pump comprising a pump cylinder having a valve seat in its base, a pump plunger adapted to be reciprocated in the cylinder of the pump and having a fixed valve head at its inner end conforming to said seat and adapted to be seated therein when moved to the inner limit of its movement, supply and outlet passages entering said valve seat adapted to be closed when the valve head is seated therein.

7. A manually operable fluid pump comprising a pump cylinder and pump plunger operable therein, said cylinder having one end closed by means of a conical valve seat forming an extension of the cylinder, a fluid passage entering the cylinder through the conical wall of the seat, and a conical head on the inner end of the plunger adapted to close said passage when the head is forced into said conical opening.

8. A manually operable fluid pump comprising a pump cylinder and a pump plunger operable therein, said cylinder having one end closed by means of a conical valve seat forming an extension of the cylinder, a fluid passage entering the cylinder through the conical wall of the seat, a conical head on the inner end of the plunger adapted to close said passage when the head is forced into said conical opening, a spring within said cylinder adapted to force the plunger to the inner limit of its movement.

9. In a priming device for internal combustion engines, a pump cylinder having a pump plunger operable therein, the pump base being formed to interchangeably receive and hold a reservoir in two relative positions to adapt the pump cylinder to be placed either vertically or horizontally.

10. A combined manually operable pump 65 and a supply reservoir, comprising a pump

cylinder and a reciprocatable plunger in said cylinder, in combination with a fluid reservoir and means for removably securing the reservoir in any one of two relative positions to adapt the pump cylinder to be placed either in vertical or horizontal position.

11. In a manually operable fluid pump, a pump plunger reciprocatable therein, a screw threaded cover or cap secured to the base of the pump, an open topped receptacle adapted to be screwed into said cap and a spring bail adapted to embrace the receptacle and to retain it in position.

12. A manually operable fluid pump, in combination with a removable fluid supply reservoir having a screw threaded connection to the pump and means carried by the pump adapted for frictionally engaging the receptacle to prevent its retrograde movement.

13. A manually operable pump, in combination with a supply reservoir adapted to be removably mounted thereon, a resilient U shaped bail pivotally mounted on the pump adapted to engage the bottom of the reservoir with a yielding pressure and means for lengthening the bail to remove it from contact with the reservoir.

14. A manually operable pump, in combination with a reservoir adapted to be removably mounted thereon, said pump and reservoir having mutually engaging threaded portions, and a U shaped bail of spring metal pivotally connected to the pump adapted to engage the bottom of the reservoir and thereby prevent the reservoir from retrograde movement, the sides of the bail being bowed outwardly, thereby adapting the bail to be lengthened when the sides of the bail are pressed inwardly.

15. In a reciprocating pump, a pump cylinder having a conical valve seat in its base, a fluid supply passage entering said base through the bottom of said seat and connecting the cylinder of said pump with a supply of liquid, a check valve in said passage adapted to prevent the return of the liquid from the pump cylinder to the supply reservoir, a pump plunger reciprocatable in said cylinder, a conical head on the inner end of said plunger conforming to said seat and adapted to be forced into the seat, and a relief passage in said head at one end opening into the bottom end thereof and at the other end opening into said cylinder above the head and adapted to permit the escape of fluid from beneath the head into the cylinder at times when the plunger is forced to its seat.

16. A pipe connection adapted to removably connect an auxiliary supply pipe to the inlet manifold of a gas engine for supplying a priming fluid thereto, said connection comprising a threaded pipe nipple, in combination with a U shaped cross bar piv-

totally mounted upon one end of the nipple, the inner end of the nipple being capped or closed and provided with a plurality of oppositely disposed outlet openings adapted 5 to project the fluid from the inner end of the nipple longitudinally through the U shaped cross bar in opposite directions, means carried by the opposite end of the nipple for connecting a pipe thereto, and 10 adjustable means carried by the nipple for removably clamping the connection to an inlet manifold.

17. A pipe connection adapted to connect a fluid pump to an inlet manifold of an 15 internal combustion engine comprising a threaded tube, a U shaped cross bar pivotally attached to one end of the tube, said end of the tube being closed and provided

with oppositely disposed outlet openings adapted when the cross bar is arranged at 20 right angles to the nipple to permit the inlet of gas to the manifold, the opposite end of the nipple being adapted to be connected by means of a pipe to the pump, and adjustable means carried by the nipple for clamping 25 the nipple in position on the manifold with the cross bar against the inner surface thereof.

In testimony whereof I have hereunto subscribed my name in the presence of two 30 subscribing witnesses.

JOHN L. PARKES.
